UNITED STATES PATENT OFFICE.

LEON W. ROSENTHAL, OF NEW YORK, N. Y., AND GUSTAVE J. LANG, OF WEEHAWKEN, NEW JERSEY, ASSIGNORS TO ARTHUR T. MURRAY, OF ALLENTOWN, PENNSYLVANIA.

RENEWABLE FUSE.

1,378,135.

Specification of Letters Patent. Patented May 17, 1921.

Application filed December 24, 1918. Serial No. 268,134.

To all whom it may concern:

Be it known that we, LEON W. ROSENTHAL, a citizen of the United States, residing at 106 Central Park west, in the city, county, and 5 State of New York, and GUSTAVE J. LANG, a citizen of the United States, residing at 849 Boulevard east, Weehawken, in the county of Hudson and State of New Jersey, have invented certain new and useful Improvements 10 in Renewable Fuses; and we do hereby declare the following to be a full, clear, and exact description of the invention, such as will enable others skilled in the art to which it appertains to make and use the same.

15 The present invention relates to renewable fuses of the kind which consists of a permanent fuse holder with terminals for connecting it in an electric circuit, and a renewable fuse adapted to be inclosed by the 20 holder and electrically connected in a detachable manner to the terminals thereof. The object of the invention is to provide a permanent and comparatively cheap fuse holder which, when assembled, gives reliable 25 and permanent contact between it and the terminals of the inclosed fuse, and at the same time permits rapid renewal of a blown-out fuse without the use of special tools.

In the accompanying drawings illustrating 30 several embodiments of the invention, Figure 1 is a section on line 1—1 of Fig. 2 of a knife blade type of fuse; Fig. 2 is a side elevation thereof; Fig. 3 is a detail of one end of the tube; Fig. 4 is a section on line 35 4—4 of Fig. 1; Fig. 5 is a longitudinal section of a modified form of a knife blade type of fuse; Fig. 6 is a detail of one end thereof; Fig. 7 is a side elevation of a ferrule type of fuse; and Fig. 8 is a longitudinal section 40 thereof.

In all of the embodiments illustrated, the cylindrical tube 1 is open ended, and is made or formed of fiber, impregnated paper, or other suitable material. The renewable 45 fuse 2 passes diagonally through the tube and has its end portions folded over the ends of the tube to form terminals 3 lying along the outer surface thereof at opposite sides. The caps 4 are of metal and have bayonet 50 slots 5 for the side screws 6, so that the caps may be pulled off and forced on the tube without entirely withdrawing the screws. The fuse terminals have slots 7 wide enough to pass over the heads of the screws, and one

terminal projects at 8 beyond the end of the 55 cap to show a capacity marking on the fuse. The caps have openings at 9 for exhausting the gases of combustion upon blow-out of a fuse, and these openings are covered by 60 gauze 10 or other material suitable to prevent the entry of foreign matter into the tube.

In the knife blade types of fuses shown in Figs. 1 and 5, the knife blades 11 are riveted or otherwise suitably fastened to the caps to form the terminals of the fuse for 65 insertion in the spring clips of a panel board. In the ferrule type of fuse shown in Fig. 7, the caps form the terminals of the fuse and may be inserted directly in spring fingers on 70 the panel board.

In Figs. 1 to 4, the tube has a recess 12 near each end for receiving a screw-threaded bearing plate 13, and a shallower recess 14 extending to the end of the tube for accommodating the fuse terminal. Each plate, 13 is of springy metal, as brass, of the size of the recess 12. When unstressed, it is substantially flat, but when strained upon forcing the cap in place and tightening the side screws 6, it conforms to the cylindrical surface of the tube and resiliently clamps the fuse terminals 3 between it and the cap to produce a permanent and durable contact between them. The recesses 12 and 14 are 80 of such depth and configuration that neither the fuse terminals nor the bearing plates extend above the outer surface of the tube, so that the caps fit closely around the tube.

In Figs. 5 and 6, each bearing plate 15 is fastened by a rivet 16 in a recess 17 extending to one end of the tube and being of sufficient depth throughout to accommodate the plate and the fuse terminal. In this case also, the bearing plates are flat before assembly so as to resiliently clamp the fuse terminals between them and the caps.

The ferrule type of fuse shown in Figs. 7 and 8 is similar in its details of construction to the fuse of Fig. 1, excepting that the caps 18 are not provided with knife blades.

By reason of the recesses 12 in the tubes of the fuses shown in Figs. 1 and 7, the bearing plates 13 are prevented from endwise movement on the tube when the fuse is assembled. The same result is accomplished by 105 the rivet 16 in the fuse shown in Fig. 5. Thus, when the side screws 6 are in place, the caps of all embodiments are prevented

from endwise displacement on the tube. However, in addition, the tubes may be perforated at 19 to permit the entry of the side screws. If desired, the perforations may be 5 screw-threaded and the bearing plates smoothly perforated.

To renew the fuse in any of the embodiments illustrated, the side screws 6 are loosened and the caps first turned circumferentially and then withdrawn in endwise direction, by reason of the bayonet slots 5. The fuse terminals are then lifted from the screws, and the separated portions of the blown-out fuse removed from the tube. A 15 new fuse may then be extended through the tube and folded over the bearing plates, whereupon the caps may be positioned and screwed down.

Having thus described our invention what 20 we claim is:

1. A renewable fuse consisting of an open-ended tube having recesses extending along the outer surface of the tube near the ends thereof, spring bearing plates located in the 25 recesses and strained into substantial conformity with the outer surface of the tube, a fuse passing through the tube and folded over the plates to form fuse terminals, caps positioned over the open ends of the tube 30 and the fuse terminals, and means securing the caps against endwise displacement on the tube.

2. A renewable fuse consisting of an open ended tube having recesses extending along 35 the outer surface of the tube near the ends thereof, spring bearing plates located in the recesses and strained into substantial conformity with the outer surface of the tube, a fuse passing through the tube and folded 40 over the plates to form fuse terminals, caps positioned over the open ends of the tube and the fuse terminals, and side screws passing through the caps and the fuse terminals into threaded engagement with the plates

to resiliently clamp the fuse terminals between the plates and caps. 45

3. A renewable fuse consisting of an open ended tube having recesses extending along the outer surface of the tube near the ends thereof and also having perforations in said recesses, spring bearing plates located in the recesses and strained into substantial conformity with the outer surface of the tube, a fuse passing through the tube and folded over the plates to form fuse terminals, caps positioned over the open ends of the tube and the fuse terminals, and side screws passing through the caps and the fuse terminals into threaded engagement with the plates to 50 resiliently clamp the fuse terminals between the plates and the caps, said screws passing into said perforations to secure the caps 55 against endwise displacement on the tube. 60

4. A renewable fuse consisting of an open ended tube having recesses extending along the outer surface of the tube and on opposite sides near the two ends thereof and also having perforations in said recesses, spring bearing plates located in said recesses and strained into substantial conformity with the outer surface of the tube, a fuse passing diagonally through the tube and folded over the plates to form fuse terminals, caps positioned over the open ends of the tube and the fuse terminals and having bayonet slots 70 in registry with said perforations, and side screws passing through the bayonet slots and the fuse terminals into threaded engagement with the plates to clamp the fuse terminals between the plates and caps, said screws also 75 passing into said perforations to secure the caps against endwise displacement on the tube. 80

In testimony whereof, we hereunto affix our signatures.

LEON W. ROSENTHAL.
GUSTAVE J. LANG.
